UNITED STATES PATENT OFFICE

2,545,411

DEVICE FOR REGULATION OF THE RESIST-
ANCE OF AN ELECTROLYTIC CELL

Roger Joseph Perret-Bit, Chambery, France, assignor to Compagnie de Produits Chimiques et Electrometallurgiques Alais, Froges et Camargue, Paris, France, a corporation of France

Application October 29, 1945, Serial No. 625,387
In France April 7, 1944

Section 1, Public Law 690, August 8, 1946
Patent expires April 7, 1964

4 Claims. (Cl. 204—225)

1

The present invention relates to electrolytic cells and more particularly to an electrolytic cell having apparatus for the control thereof.

It is well known that every electrolytic cell comprises electrodes of different polarity, anode and cathode. In certain types of cells, the resistance between the anode and cathode varies during the electrolysis. Furthermore, it is well known that electrolytic cells for the manufacture of aluminum are provided with carbon anodes that are burned gradually by the free oxygen released at their surface. In cells of this type, the anode is usually movable in a vertical direction to approach or move away from the cathode, which usually forms the bottom of the cell in which the electrolysis takes place. It has been proposed to control the action of the apparatus by keeping the voltage between the electrodes constant. However, in the case of cells where a periodic polarization occurs, this system is defective. In the case of the electrolysis of aluminum, for instance, the same amount of current may be passed through a plurality of cells and when one of the cells is subjected to anodic polarization, the voltage across its terminals is increased and the current passing through other cells located in the same circuit is decreased. The voltage on these cells decreases also and, yet, withdrawing the anodes will not overcome the difficulty and keep the voltage at the desired control value.

One object, therefore, of this invention is to provide an apparatus wherein means is provided for adjusting the interelectrode distance of an electrolytic cell so as to always obtain a desired bath resistance.

Other objects of the applicant's invention will appear from the following description of specific embodiments thereof.

The preferred embodiments of the present invention, as hereinafter described with reference to the drawings, are given by way of example only. In the drawings:

Figure 1 is a diagrammatic view of an arrangement according to the present invention for measuring the resistance of the bath of an electrolytic cell, and, eventually, controlling this resistance.

Figure 2 is a diagrammatic view of another arrangement according to the present invention for indicating the voltage that should exist across the terminals of the electrolytic cell if the resistance of the bath were adjusted to the desired value, the indication being independent of the current flowing through the cell at the time of the measurement.

2

Figure 3 is a diagrammatic showing of a device according to the present invention for signalling at any time the difference, if any, between the actual value of the resistance of the bath and the desired value of this resistance, with a view to enabling adjustment of the resistance in question.

Figure 4 is a diagrammatic view of another embodiment of the instant invention.

10. In the arrangement illustrated in Figure 1, the applicant makes use of a balanced relay having crossed actuating coils 1 and 3 mounted on a common pivot 35, the principle of which is well known in the art. On one of the coils 1 of this apparatus, there is impressed by means such as leads 31 and 32 a voltage proportional to the amount of current flowing through the electrolytic cell 10, said cell having electrodes 25 and 26 with power leads 27 and 28 attached thereto, by means such as shunt 2 or other equivalent means, for instance, a direct current transformer of a known type. The other coil 3 has impressed thereon by means such as leads 33 and 34 a potential difference proportional to the voltage 15 across the terminals of the electrolytic cell reduced by an amount to be described later, and supplied by a battery 4 and a potentiometer 5 associated therewith. Variable resistances or rheostats 6 and 7 are provided for adjusting the proportionality factors of the device. The device further includes connections 8 and 9 contacted by an actuated member 30 operative by the crossed coils to act either on a signalling means or an automatic inter-electrode resistance adjusting means, such as the motor-driven electrode-adjusting means generally designated 24.
20. With such an arrangement, the angle of deflection of the coils and their actuated member for contacting the connections 8 and 9, that is, 25. 30. 35. 40. 45.

Therefore,

$$\text{tangent } \theta = \frac{K_1(U-u)}{K_2 I}$$

By means of the potentiometer 5, the value of u can be adjusted to be equal to the value of e , the electromotive force of the cell 10. When this is done, since U equals the voltage impressed on the cell plus the internal electromotive force of the cell itself;

$$\text{tangent } \theta = \frac{K_1 R}{K_2}$$

Thus it can be seen that the device permits the obtaining, at any time, of the value of the inter-electrode resistance R . It further permits, through connections 8 and 9, of adjusting this resistance to a desired relationship to the current supply.

When several electrolytic cells are connected in series, the adjustment of the inter-electrode distance between the electrodes in any given cell may be based upon the indications supplied by a voltmeter 11, shown in Figure 2, connected by leads 33 and 34 in shunt across the terminals of each cell 10 having electrodes 25 and 26 with power leads 27 and 28 attached thereto. However, this voltmeter gives reliable indications for use in adjusting the inter-electrode spacing and resistance only so long as the current is of a nominal value for which the cell has been set. If the cell undergoes an anode effect and the current is, thus, modified considerably, the above-described voltmeter method cannot be used.

With the arrangement shown in Figure 2, a measuring device 12 indicates at any time, irrespective of the current flowing through the cells, the value of the voltage that should exist across the particular cell under consideration, so that the resistance of that cell can be adjusted accordingly. The measuring device may be a voltmeter connected to the terminals of a potentiometer 13, which, in turn, is in series with similar potentiometers corresponding to other cells, respectively. The current flowing through these potentiometers originates in a device 14 which may be a direct-current transformer or a shunt connected to the line feeding the cells and is brought to said potentiometers through leads 31 and 32. With this arrangement, the voltage on the voltmeter 12 is proportional to the current flowing through the cell. However, the scale on the voltmeter is so arranged that the pointer shows a voltage proportional to the current but increased by a constant voltage equal to the internal electromotive force of the cell, since this latter force makes itself felt on the terminals of the cell and must be taken into consideration.

Potentiometer 13 is adjusted in such manner that, when the value of the current is the nominal value, the voltmeter 12 exactly indicates the desired value of the voltage to be impressed on the cell, this adjustment being different for the various cells. It then becomes necessary only to adjust the inter-electrode distance to the point where the readings of the voltmeter 11 and 12 of a given cell coincide and the inter-electrode resistance has then been adjusted to the desired amount.

This results from the following derivation:

The deflection θ_1 of the voltmeter 12 is:

$$\theta_1 = K_1 I$$

but, due to the peculiar graduation of this voltmeter, the reading θ_2 is as follows:

$$\theta_2 = K_1 I + u$$

and, if u is chosen so as to be equal to e , the internal electromotive force of the cell,

$$\theta_2 = K_1 I + e$$

If the potentiometer 13 has been adjusted so that, when the current through the cell is equal to the nominal value, the reading on the voltmeter 12, that is θ_2 , is equal to the voltage existing across said cell when the inter-electrode resistance has the desired value, R_0 , then:

$$\theta_2 = K_1 I + e = R_0 I + e$$

In other words, as long as this adjustment of the potentiometer 13 is maintained, $K_1 = R_0$ and, whatever the current intensity I through the cell, the value θ_2 read on the voltmeter 12 will be the voltage that should exist across the cell when the inter-electrode resistance is adjusted to R_0 , the desired value.

In the embodiment shown in Figure 3, the applicant makes use of a differential balanced relay of a known type having two actuating coils 1 and 3 which are movable in the air gap of a permanent magnet. Coil 1 is subjected by means such as leads 31, 32 to a voltage proportional to the current flowing through the electrolytic cell 10 having electrodes 25 and 26 with power leads 27 and 28 attached thereto, obtained by means such as shunt 2, or the like. The other coil 3 is subjected by means such as leads 33, 34 to a voltage proportional to the difference between the voltage across the cell 10 and a voltage of the value of the internal electromotive force of the cell. In the example, the latter voltage is supplied by a battery 4 associated with a potentiometer 5. Rheostats 6 and 7 are provided for adjusting the proportionality of the device. Two opposed springs, not shown, are provided to act upon the actuated member 30 of the relay so as to exert no force thereon when it is in a median position. On the other hand, they resist slightly the torque exerted by the fields of the coils 1 and 3. The actuated member will, of course, contact either connections 8 or 9 to set the adjusting means 24 in motion when the difference between the electromagnetic fields of the coils 1 and 3 gets high enough. Accordingly,

$$\epsilon = a_1 - a_2$$

where ϵ is the driving torque exerted on the actuated member, a_1 is the ampere-turns of coil 1 and a_2 is the ampere-turns of the coil 3. Generally speaking, when ϵ is equal to zero, both of the connections are open.

Now, $a_1 = K_1(U-u)$ and if the constant value u is chosen equal to the value of e , the electromotive force of the cell,

$$a_1 = K_1(U-e)$$

But the voltage across the electrolytic cell, that is, U is equal to $RI+e$, R being the inter-electrode resistance, I the current flowing through the cell, and e the internal electromotive force of the cell. Therefore:

$$a_1 = K_1(RI+e-e) = K_1RI$$

70 Also:

$$a_2 = K_2 I$$

So,

$$\epsilon = K_1 R I - K_2 I = I(K_1 R - K_2)$$

Therefore, if R_0 is the desired value of the inter-electrode resistance of the cell, it is sufficient to choose K_1 and K_2 so that:

$$\frac{K_1}{K_2} = R_0$$

and the ϵ will equal zero and the actuated member of the relay will be balanced in neutral position between the connections 8 and 9. The adjustment of K_1 and K_2 is done by means of potentiometers 6 and 7. Of course, when R is smaller than

$$\frac{K_1}{K_2}$$

the connection 9 will be closed, the adjusting means 24 being actuated correspondingly to adjust the inter-electrode spacing and resistance. Furthermore, it can be seen that this action is independent of the current flowing through the cell.

In the embodiment illustrated in Figure 4, the applicant makes use of a differential balanced relay of the known type having two actuating coils movable in the air gap of a permanent magnet. One of these coils, that is, 20 has by means such as leads 31 and 32 a voltage proportional to the current flowing through the cell 10, which is provided with electrodes 25 and 26 having power leads 27 and 28 attached thereto, increased by a voltage equal to the internal electromotive force of the cell and brought about by means of a battery 19 associated with a potentiometer 18. The first-mentioned voltage above is brought about by means such as a shunt multiplier 16, a simple shunt, a direct current transformer, or any similar device giving a voltage proportional to the current flowing through the cell. As illustrated, this embodiment contemplates the use of a plurality of cells operating in the same circuit and the potentiometers 17 for the coils 20 make use of the same shunt multiplier 16.

The other coil 15 of the relay is subjected by means such as leads 33 and 34 to a voltage proportional to the voltage across the terminals of the cell. Two springs, not shown, are mounted to act in opposition on the actuated member of the relay, so that said member remains ordinarily in a neutral position between connections 21 and 22 which lead to the adjusting means generally designated 24. The actuated member moves under the influence of the opposed electromagnetic fields of the coils 20 and 15 and contacts the connection 21 or the connection 22, depending on which influence is greater, to actuate the adjusting means 24 in a corresponding manner. Now,

$$a_1 = K_1(K_2I + u)$$

where a_1 is the ampere-turns of the coil 20, I is the current flowing through the cells and u is the voltage across the potentiometer 18 brought about by the battery 19.

Also,

$$a_2 = K_3U$$

where a_2 is the ampere-turns of the coil 15 and U is the voltage across the cell.

Consequently,

$$\epsilon = K_1K_2I + K_1U - K_3U$$

ϵ being the difference between the ampere-turns of coil 20 and those of coil 15. Since,

$$U = RI + e$$

where R is the inter-electrode resistance of the cell and e is the internal electromotive force thereof,

$$\epsilon = K_1K_2I + K_1U - K_3RI - K_3e$$

5 If the potentiometer is adjusted so that $K_1u = K_3e$ then

$$\epsilon = K_1K_2I - K_3RI$$

Now, if we adjust the potentiometer 17 so that 10 R_0 , the desired inter-electrode resistance is equal to the ratio of K_1K_2 to K_3 , or

$$R_0 = K_1 \frac{K_2}{K_3}$$

15 then the value of ϵ for the particular cell whose potentiometer has been so adjusted will be as follows:

$$\epsilon = K_3R_0I - K_3RI = K_3I(R_0 - R)$$

20 So that when the actual inter-electrode resistance R is equal to the desired value R_0 , the actuated member of the relay will be in a neutral position. If, however, the value of R goes above or below the desired value R_0 , the actuated mem-

25 ber will contact the proper connection 21 or 22, and the adjusting means 24 will be set in motion to adjust the inter-electrode space and the resistance R to the proper value.

While I have disclosed in the above description 30 what I deem to be practical and efficient embodiments of my invention, it should be understood that I do not wish to be limited thereby. Changes may be made in the arrangement, disposition, and form of the parts without departing from the principle of the present invention 35 as brought out in the accompanying claims.

Having thus described my invention, what I claim as new and desire to secure by Letters Patent is:

40 1. An electrolytic apparatus comprising a cell for holding an electrolyte, two electrodes in said cell, adjusting means for moving one of said electrodes toward and away from the other electrode, power leads provided on said electrodes for connection with a direct-current source, a balanced relay comprising two opposed actuating coils and an actuated member, said actuated member moving between a connection for causing the adjusting means to move said one electrode toward the other electrode and a connection for causing said 45 adjusting means to move said one electrode away from said other electrode, means connected across said power leads for impressing on one of said coils a voltage proportional to the inter-electrode resistance, and means connected to one of said coils a voltage proportional to the current flowing between the electrodes.

50 2. An electrolytic apparatus as recited in claim 1, wherein: the means for impressing on one of said coils a voltage proportional to the inter-electrode resistance includes a potentiometer in series with the coil and a battery shunted across said potentiometer.

55 3. An electrolytic apparatus comprising a plurality of units connected in series each having a cell for holding an electrolyte, two electrodes in said cell, adjusting means for moving one of said electrodes toward and away from the other electrode, power leads provided on said electrodes for connection with a direct-current source, a balanced relay with each unit having two opposed actuating coils and an actuated member, said actuated member moving between a connection 60 for causing the adjusting means to move said

one electrode toward the other electrode and a connection for causing said adjusting means to move said one electrode away from said other electrode, means connected across said power leads for impressing on one of said coils a voltage proportional to the inter-electrode resistance, and means connected to one of said power leads for impressing on the other of said coils a voltage proportional to the current flowing between the electrodes, said means for impressing a voltage proportional to the current flowing between the electrodes being common to like coils in all of the units. 10

4. An electrolytic apparatus as recited in claim 3, wherein: said means for impressing on the other of said coils a voltage proportional to the current flowing between the electrodes acts through a potentiometer having a battery shunted thereacross. 15
